UNITED STATES PATENT OFFICE.

HARRISON D. BOYER, OF PHILADELPHIA, PENNSYLVANIA, ASSIGNOR TO BOYER
MANUFACTURING COMPANY, A CORPORATION OF NEW JERSEY.

LUBRICATOR.

1,121,579.

Specification of Letters Patent. Patented Dec. 15, 1914.

Application filed February 24, 1914. Serial No. 820,489.

To all whom it may concern:

Be it known that I, HARRISON D. BOYER, a citizen of the United States, residing at Philadelphia, in the county of Philadelphia and State of Pennsylvania, have invented 5 new and useful Improvements in Lubricators, of which the following is a specification.

My invention relates to new and useful 10 improvements in Lubricators, and has for its object to provide an exceedingly simple and effective device of this character which will feed a lubricant to a bearing under pressure; will maintain approximately the same 15 pressure upon said lubricant so as to insure the steady feeding of the same and will throw a signal when the pressure has been released from off the lubricant.

With these ends in view this invention 20 consists in the details of construction and combination of elements hereinafter set forth and then specifically designated by the claims.

In order that those skilled in the art to 25 which this invention appertains may understand how to make and use the same, I will describe its construction in detail, referring by numeral to the accompanying drawing forming a part of this specification, in 30 which—

Figure 1, is an elevation of my improved lubricator. Fig. 2, is a central vertical section thereof showing the signal up. Fig. 3, is a section of the upper portion of the lubricator taken at right angles to Fig. 2 showing 35 the mechanism in the position assumed when pressure is exerted upon the lubricant. Fig. 4 is a top plan view. Fig. 5, is a bottom plan view. Fig. 6, is a section at the line 40 $\alpha-\alpha$ of Fig. 2; and Fig. 7, is a central vertical section of the upper member of the lubricator, showing a modification of the means for exerting pressure upon the lubricant.

In carrying out my invention as embodied 45 in Figs. 1 to 6 inclusive, 1 represents the body of the device which is in tubular form, the lower end thereof being threaded into the base 2, the latter terminating in a 50 threaded nipple 3, by which it may be screwed into the threaded opening to a machine bearing in the usual manner. As here shown the base has a wrench hold formed thereon and inside of this base is located a

funnel preferably made of copper or other 55 high heat conducting material, the spout of said funnel extending through the nipple and secured against displacement by having its lower end flanged outward as clearly shown in Fig. 2. This body base and funnel form the lower member of the device, 60 while the upper member consists of the tubular section 5 and top 6, the latter being here shown as threaded on the upper end of the tubular section. The upper member is 65 threaded into the lower member as clearly shown, and has fitted therein a plunger 7 which is forced downward by the spring 8. 9 represents a post which is secured to the plunger and projects upward therefrom and 70 has formed therein a slot 10 in which the link 11 is hooked, the upper end of said link being hooked into the opening 12 of the signal disk 13. By this arrangement when the plunger is forced to its lower limit of movement the signal disk will be so actuated as 75 to be brought to a vertical position as clearly shown in Figs. 1 and 2, but when the plunger is forced upward against the action of the spring the signal disk will be released 80 and will fall by gravity to the position shown in Figs. 3 and 4.

To charge the lubricator the upper member is removed by screwing it out of the body, the grease or the lubricant placed in 85 the body and the upper member replaced and threaded downward when the plunger will be forced upward in the upper member until the post 9 comes in contact with the top and this upward movement of the post 90 will lower the signal, but as the lubricant is gradually fitted to the bearings by the pressure exerted thereon by the plunger, the consequent movement of the plunger will bring the upper wall of the slot 10 into contact 95 with the link 11 when the plunger has nearly reached its lower limit and the lowest slight movement of the plunger thereafter in finally reaching its lower limit will elevate the signal and indicate to the attendant that 100 the pressure has been removed from the lubricant. It is only necessary for the attendant to screw down upon the upper member until the post 9 again contacts with the top, preventing further movement of the 105 upper member when the operation just described will be repeated. The limitation of the compression of the spring by the post

coming in contact with the top prevents the attendant from putting an overpressure upon the lubricant, and as the spring acts through only a small portion of its length, the pressure upon the lubricant will vary but slightly, giving an uneven feed of the lubricant. When the upper member has been threaded downward to its lowest limit and the plunger has reached its lowest limit of movement, the heat transmitted from the bearing to the copper funnel will be sufficient to cause the remaining lubricant to continue to feed to the bearing so that after the signal is thrown, considerable time will elapse before the lubricant will stop feeding to the bearing.

I have shown the upper member made up of a tubular section threaded into the base and the upper member made up of a corresponding tubular member threaded into the top. These two members may be made in one piece, either by drawing the metal into shape or by casting.

In Fig. 7 I have shown a slight modification of the means for exerting pressure upon the lubricant which consists of a hollow plunger 13 to which the post 9 is secured and inside of this plunger is located a disk 14 sliding upon the rod 15, its downward movement being limited by the nut 16. By this modified form of construction the air is trapped in the plunger 13 when the upper member is screwed into place and the threading of the latter downward upon the lubricant will cause said lubricant to rise in the hollow plunger carrying the disk 14 upward therewith, and compressing the air. As the air thus compressed reaches a pressure above the tension of the spring 8, the plunger itself will move upward within the upper member thereby lowering the signal. The disk 14 is not intended to be fitted air tight in the plunger but only serves as a cover for the lubricant to prevent the compressed air above the same from blowing through it in holes. This construction permits the lubricant to be fed by air pressure and when this air pressure has dropped below a predetermined point the spring will move the plunger downward sufficiently to throw the signal, thus indicating to the attendant that the lubricator needs further adjustment or refilling as the case may be.

Of course I do not wish to be limited to the exact details of construction as here shown, as these may be varied within the limits of the appended claims without departing from the spirit of my invention.

Having thus fully described my invention, what I claim as new and useful, is—

1. In a lubricator the combination of a base, a body secured thereto, an upper member consisting of a tubular section adapted to thread into the body and a top secured to the upper end of the tubular member, a

spring actuated plunger fitted to slide within the tubular section and a signal and means for actuating said signal on the plunger.

2. In a lubricator a plunger a signal adapted to lie against one of the outer walls of the lubricator and means connecting the plunger and signal whereby said signal may be thrown to a vertical position at the end of the movement of the plunger.

3. In a lubricator provided with a plunger a signal adapted to lie in a normal horizontal position and be thrown to the vertical position by the plunger at the end of the movement of said plunger.

4. A lubricator consisting of a body and an upper portion, the latter threaded into the former, a plunger fitted to slide within the upper portion, a signal engaging the outside of the upper portion and means passing through the upper portion for connecting the plunger with the signal whereby said signal lies against the upper portion when the plunger is operating and is thrown or elevated when at the end of the plunger stroke.

5. A grease cup consisting of a body and an upper portion the latter threaded into the former, said upper portion having an opening in its top provided with beveled surrounding walls, a plunger fitted to slide within the upper portion, a spring for actuating said plunger, a signal, means for connecting the signal and plunger whereby a portion of said signal may be drawn into the opening in the top of the upper portion at the end of the plunger stroke to throw said signal.

6. In combination with a lubricator a plunger adapted to force the lubricant from the lubricator to the bearing, a spring for actuating the plunger in one direction, a signal member so located upon the lubricator as to lie flat thereon while the lubricant is being fed and means connecting the plunger and the signal member, said means adapted to elevate the signal member after the manner of a semaphore at the end of the stroke of the plunger.

7. In combination with a lubricator a spring actuated plunger adapted to feed the lubricant contained in the lubricator to a bearing, a signal disk located upon the top of the lubricator and means connecting the plunger with said signal disk in such manner that said signal disk will lie flat upon the lubricator during the feeding of the lubricant by the movement of the plunger, but be elevated at the end of the stroke of said plunger.

8. A lubricator consisting of a body member, a top member threaded in the first named member, a plunger fitted to slide in the top member, a spring for forcing said plunger downward, a signal disk located at

the top of the top member, and means connecting the plunger with the signal disk in such manner that said signal disk will lie flat throughout a portion of the movement of the plunger, but brought to a vertical position at the end of the stroke of said plunger.

In testimony whereof, I have hereunto affixed my signature in the presence of two subscribing witnesses.

HARRISON D. BOYER.
